DESIGN FOR A SHOE TOE-CAP STRETCHER

Richard Pfifferling, New York, N. Y., assignor to Richard Rosen, Long Island City, N. Y.

Application April 30, 1947, Serial No. 138,716

Term of patent 3½ years

(Cl. D7—3)

To all whom it may concern:

Be it known that I, Richard Pfifferling, a citizen of the United States, residing at the city, county, and State of New York, have invented a new, original, and ornamental Design for a Shoe Toe-Cap Stretcher, of which the following is a specification, reference being had to the accompanying drawings, forming part thereof, in which:

Fig. 2 is a side view thereof;

Fig. 3 is a top plan view;

Figs. 4 and 5 are views in section on the lines 4—4 and 5—5, respectively, of Fig. 2; and,

Fig. 6 is a section on line 6—6 of Fig. 1.

I claim:

The ornamental design for a shoe toe-cap stretcher, substantially as shown.

RICHARD PFIFFERLING.
